UNITED STATES PATENT OFFICE.

CHARLES CARROLL JOHNSTON, OF JACKSON, MISSISSIPPI.

COIN-HOLDER.

SPECIFICATION forming part of Letters Patent No. 293,033, dated February 5, 1884.

Application filed December 15, 1883. (Model.)

To all whom it may concern:

Be it known that I, CHARLES C. JOHNSTON, of Jackson, in the county of Hinds and State of Mississippi, have invented a new and Improved Coin-Holder, of which the following is a full, clear, and exact description.

The object of my invention is to provide a new and improved receptacle for holding coins, &c., which holder is simple in construction and cheap.

The invention consists of two semi-cylindrical sections or casings hinged to each other at the adjoining ends, into which sections the coins are placed.

Reference is to be had to the accompanying drawings, forming part of this specification, in which similar letters of reference indicate corresponding parts in all the figures.

Figure 1 is a perspective view of my improved coin-holder. Fig. 2 is a longitudinal sectional elevation of the same partly opened. Fig. 3 is a cross-sectional elevation of the same closed. Fig. 4 is an end view of the same closed.

The casing is formed of two semi-cylindrical sections or casings, A, provided with semi-circular heads B, which casings are united at one end by a flexible strip, C, of paper, cloth, &c., glued to the heads. To one of the opposite heads a strip or tag, D, is secured, which has the under side of its free end provided with gum, mucilage, or other adhesive substance. The free ends of the casings A are swung apart, and the coins are placed between and into

them, and then the holder is closed and secured by means of the strip which is moistened and pressed on the free head of the other casing or section. The value of the coins contained in the holder can then be written, printed, or stamped on the strip D. The holder can be made of various sizes and of pasteboard, stiff paper, stiffened fabric, leather, or other suitable material. The sections A can be hinged together in any other suitable manner.

Having thus fully described my invention, I claim as new and desire to secure by Letters Patent—

1. A coin-holder made substantially as herein shown and described, and consisting of semi-cylindrical sections held together by a hinge-joint at one end, as set forth.

2. In a coin-holder, the combination, with two semi-cylindrical sections, of a flexible strip secured to the adjoining ends of two sections, substantially as herein shown and described.

3. In a coin-holder, the combination, with the two semi-cylindrical sections A, having heads B, of the flexible strip C, secured to two adjoining heads, and of the strip D, secured to one of the opposite heads, substantially as herein shown and described.

CHARLES CARROLL JOHNSTON.
